HEATER FOR FISH HOUSES

Albert L. Pearson and Clarence A. Pearson,
Benson, Minn.

Application February 6, 1958, Serial No. 49,525

Term of patent 14 years

(Cl. D81--1)

FIG. 1

FIG. 2

FIG. 3

FIG. 4

Fig. 1 is a view in perspective of a heater for fish houses, showing our new design;

Fig. 2 is a view in perspective as seen from the bottom and from the right of Fig. 1.

Fig. 3 is a view in side elevation taken from the side opposite that of Fig. 1; and

Fig. 4 is a view in end elevation as seen from the right of Fig. 3.

We claim:

The ornamental design for a heater for fish houses, as shown.
